(57) **CLAIM**

The ornamental design for a car code reader and scanner diagnostic tool, as shown and described.

DESCRIPTION

FIG. 1 is a top, front and right side perspective view of a car code reader and scanner diagnostic tool showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled "9" in FIG. 7; and,

FIG. 10 is an enlarged view of the portion labeled "10" in FIG. 7.

The broken lines show the portion of the car code reader and scanner diagnostic tool that form no part of the claimed

(Continued)

design. Dot-dash broken line rectangular frame defines the boundary of an enlarged view and form no part of the claimed design.

1 Claim, 10 Drawing Sheets
